Primary Examiner — Thomas Johannes*Assistant Examiner* — Catherine Posthauer(74) *Attorney, Agent, or Firm* — Haynes and Boone, LLP(57) **CLAIM**

The ornamental design for a tagine, as shown and described.

DESCRIPTION

FIG. 1 is a front perspective view of a tagine showing our new design;

FIG. 2 is a front view thereof, the rear view being a mirror image of the front view;

FIG. 3 is a right side view thereof, the left side view being a mirror image of the right side view;

FIG. 4 is a top view thereof; and,

FIG. 5 is a bottom view thereof.

The features shown in broken lines are portions of the tagine forming no part of the claimed design. The features shown in long dash-short dash bolded broken lines indicate the bounds of the claimed design and otherwise form no part of the claimed design.
